UPRIGHT PIANO ACTION

Chauncey D. Bond, York, Pa., assignor to Weaver
Piano Company, Inc., York, Pa., a corporation
of Pennsylvania

Application March 9, 1936, Serial No. 67,757

6 Claims. (Cl. 84—240)

This invention relates to key operated stringed musical instruments such as pianos, and more particularly to upright pianos of the miniature type.

5 An object of the invention is to provide an improved upright piano in which the level of the key board can be disposed at any desired height with respect to the standard upright piano action, the sound board, and the iron frame of the instrument.

10 Another object of the invention is to provide an improved upright piano action in which there is no locked contact between the key and the action.

15 Another object of the invention is to provide an improved upright piano action in which the keys may be removed without disturbing the regulation.

20 Another object of the invention is to provide an improved upright piano so constructed that the action can be removed without disturbing the regulation.

25 Another object of the invention is to provide an improved upright piano having improved means for adjusting the mechanism so that the mechanism can be easily regulated to take out lost motion.

30 Another object of the invention is to provide an improved upright piano of the character mentioned, which is simple in construction and reliable and exact in function under all conditions of service.

35 The invention also comprises certain new and useful improvements in the construction, arrangement and combination of the several parts of which it is composed as will be hereinafter more fully described and claimed.

In the accompanying drawings:

40 Figure 1 is an end elevation of a miniature upright piano constructed according to the present invention with parts broken away and in vertical section;

45 Fig. 2 is a side view partly in section of the principal parts of the action of the upright piano shown in Fig. 1; and

50 Fig. 3 is a detail perspective view of the action lift member operatively associated with the key and the wippen for operating the action shown in Fig. 2.

55 In the construction of miniature upright pianos having the standard action mechanism, the disposition of the key board is so low as to greatly inconvenience the average piano player. This is due to the fact that the action is disposed in such a position in the piano case that the keys are lo-

cated too close to the floor to permit a player while sitting on a piano stool or bench to position his legs, especially his knees, beneath the key bottom.

According to the present invention, miniature upright pianos of very small size and embodying the standard actions and keyboards can be constructed with the keyboard positioned at any level desired with respect to the action, so that the keys will operate the action in the usual manner. 5 Such improvement in the construction of miniature upright pianos is accomplished by shortening the length of the key bottom, key frame and the keys, and operatively connecting the inner end of the shortened key with the wippen by an 10 improved action lift in the nature of a Z-shaped member constructed in the manner to be herein-after more fully described.

Referring to the drawings, the standard upright piano action comprises a wippen 11 which 20 is pivotally mounted upon an action rail 12 by means of a wippen flange 13. A hammer butt 14 is pivotally mounted upon the action rail 12 by means of a flange 15. A jack 16 is pivotally carried upon the wippen 11 by means of a flange 25 17. The hammer butt 14 carries a hammer shank 18 which at its end supports a hammer 19. This hammer normally rests against a hammer rail 20. These parts are those ordinarily to be found in 30 ordinary upright pianos and require no further description.

The key 21 is pivotally mounted on a key frame 22, which latter is supported by a key bottom 23 of usual construction.

In accordance with the present invention the 35 key 21, key frame 22 and key bottom 23 are all mounted in the piano at a point above the wippen 11, as shown in Figs. 1 and 2.

In the prior construction of standard upright pianos the inner end of the key 21 terminated beneath the wippen and the inner end of the key carried a capstan screw, the head of which engaged a felt pad carried by the underside of the wippen. The purpose of the capstan screw was to enable the inner end of the key to at all times 45 be operatively engaged with the wippen.

With the key 21 and its supporting structure located above the wippen or at a point other than the standard construction, it is necessary to provide some means for operatively connecting 50 the key 21 with the wippen 11 so that when the key is actuated the wippen will be actuated to operate the mechanism so that the hammer 19 will strike a musical string 24 in the usual manner.

According to the present invention the means for operatively connecting the key 21 with the wippen comprises an action lift 25 in the form of an elongated member of substantial Z-form. 5 The upper end of the action lift 25 has a laterally extending arm 26 which overlies the inner end of the key 21, and the lower end of the action lift 25 is formed with an arm 27 which extends laterally in a direction opposite to the arm 26 and terminates in an upwardly extending lug 28, which engages a felt pad 29 on the underside of the wippen 11.

In order that the lug 28 can be at all times maintained in contact with the wippen 11, the 15 underside of the arm 26 is formed with an arcuate surface 30 which constitutes a bearing for engaging the key 21.

Formed in the arm 26 on opposite sides of the arcuate bearing surface 30, are openings 31 20 through which are inserted screws 32 which are mounted in the key 21 as shown in Fig. 2.

By this construction the relative position of the action lift 25 can be regulated or adjusted so that when the key is mounted on the key frame 25 the inner end or lug 28 of the action lift 25 will bear against the underside of the wippen whereby the key will be operatively connected with the wippen in the customary manner.

One of the features of the present invention 30 resides in the fact that the usual piano key which, as is well known, is supported upon a center pin 33 carried by a center rail 34 of the key frame 22, and key pin 35 carried by the usual front rail 36, can be taken out or removed from the piano 35 without disturbing the regulation. Furthermore, by the above described construction it will be noted that there is no locked contact between the key and the action, and the key can be readily removed in the usual manner by first raising the 40 outer end of the key to disengage the same from the pins 33 and 35, since the inner end of the action lift arm will pass readily underneath the outer end of the wippen 11.

In Fig. 1 I have indicated by a broken line the 45 usual location of the key bottom in the standard miniature upright pianos. It will be appreciated that by my present invention the key bottom can be located at a point considerably above the usual disposition of this part of upright pianos.

50 While in the instant case the key bottom is located slightly above the wippen of the standard upright piano action, it will be appreciated that the key bottom can be located at any other relative position desired and when such relocation of the key board is effected it is only necessary to construct the intermediate vertical portion of the action lift 25 longer or shorter as the case may be, so that when said action lift is 55 mounted on the key 21 its inner end 28 will operatively engage the underside of the wippen 11.

Changes may be made in the details of construction and in the arrangement of the parts

above described within certain limits without departing from the spirit of the invention.

Having thus described my invention what I claim is:—

1. In a piano action, a wippen, a key board 5 having a key pivotally mounted thereon and located in front of and above the wippen, and an arm carried by said key and comprising an upper laterally extending portion, an intermediate depending portion, a lower laterally extending portion underlying the wippen and an upwardly extending portion projecting from lower laterally extending portion for engaging the underside of the wippen.

2. In a piano action, a wippen, a key board 15 having a key pivotally mounted thereon and located in front of and above the wippen, and an arm carried by said key and comprising an upper laterally extending portion, an intermediate depending portion, a lower laterally extending portion underlying the wippen and an upwardly extending portion projecting from lower laterally extending portion for engaging the underside of the wippen, and means for adjustably mounting said arm on the key to maintain the inner end thereof in engagement with the wippen.

3. In an upright piano having a standard action, a wippen, a key disposed in front of and above the wippen, a single arm engageable with 30 said wippen for actuating the same, a pair of spaced apart screws passed through one end portion of said arm for securing said arm to the key, and a lug depending from said arm and disposed between said screws and constituting a bearing 35 for engaging said key whereby the relative position of said arm with respect to the key can be adjusted so as to maintain the opposite end of said arm in engagement with said wippen.

4. A piano action comprising a wippen and 40 mechanism operated thereby, a key, and an arm for actuating said wippen having one end adjustably fastened to the key and having its opposite end underlying and disconnected from said wippen.

5. A piano action comprising a wippen, a key disposed in front of and above the wippen, and means operatively connecting the key with the wippen, said means comprising a single arm engageable with and disconnected from said 50 wippen and having an elongated substantially vertical portion adjustably carried by the inner end of the key and having its lower end terminating at a point below said wippen and adapted to actuate the wippen when the key is operated.

6. A piano action comprising a wippen, and a key for operating said wippen having a Z-shaped extension terminating beneath and disconnected from the wippen, said extension being engageable with the underside of said wippen 60 when the key is operated.

CHAUNCEY D. BOND.
